UNITED STATES PATENT OFFICE.

GEORGE E. LITTLEFIELD, OF EAST AURORA, NEW YORK.

BROODER-HEATER.

No. 836,194.

Specification of Letters Patent.

Patented Nov. 20, 1906.

Application filed June 21, 1904. Serial No. 213,505.

To all whom it may concern:

Be it known that I, GEORGE E. LITTLEFIELD, a citizen of the United States, and a resident of East Aurora, in the county of Erie and State of New York, have invented certain new and useful Improvements in Brooder-Heaters, of which the following is a specification.

This invention relates to brooder-heaters; and it consists in the apparatus and arrangement of parts hereinafter described and claimed.

In the drawings, Figure 1 is a central vertical section through a brooder containing the present invention. Fig. 2 is a like section through the lamp and lamp-supports, showing another position of the parts. Fig. 3 is a side elevation of the connections between the drum and standard of the heater. Fig. 4 is a bottom plan view of the parts shown in Fig. 3. Fig. 5 is a central vertical section through the preferred form of the invention and on the line 5 5 of Fig. 6, and Fig. 6 is a section on the line 6 6 of Fig. 5.

In the form shown in Fig. 1 the brooder has a removable roof 1, sides 2, a bottom 3, and a floor or partition 4, separating the brooder into two chambers, the upper of which, 5, is the brooder-chamber and the lower of which, 6, is the lamp-chamber. The brooder-chamber 5 may have a suitable door, and the lamp-chamber 6 has a suitable door 7 extending into it.

The partition or floor 4 has a perforation 8, on whose edges may rest a plate 9, of sheet metal, having a perforation 10 through its center. The floor 4 rests upon cleats 4^a, fastened to the inner faces of the sides 2. A cleat 4^b may be fastened on the front edge of the floor, as shown in Fig. 1. A shallow cylindrical drum 11, having a top 12, side 13, and bottom 14, forms a part of the heat-radiator, and said-drum may contain a cone 15, of sheet metal, fastened to the top 12 of the drum and having its apex directed downward and over a perforation 16 is the bottom 14. A duct or chimney 17 from near the bottom 14 of the drum extends out of the brooder, so as to carry away the products of combustion.

A casting 18 has a cylindrical portion extending through the perforations 16 in the bottom of the drum and two downwardly-

extending rims 19 and 20. A bottom-casting 21 has two upwardly-extending rims 22 and 23 of the same diameter as the rims 20 and 19, respectively, of the upper casting. An inner sheet-metal tube 24 fits on the rims 19 and 23, and an outer sheet-metal tube 25 fits the rims 20 and 22. The outer tube has means of discharging heated air therefrom, consisting in the present case of a series of perforations 26 near its top. The bottom casting 21 has also a projecting duct 27 extending down below the floor 4 and into the lamp-chamber 6, and this duct connects with the space between the tubes 24 and 25. If now the heat from the lamp is carried through the perforation 10 and into the tube 24, the products of combustion will heat that tube and will heat the air in the space between the tubes 24 and 25, so that said air will rise through and pass out of the perforations 26 and fresh air will be drawn in through the duct 27. The products of combustion from the lamp after passing through the tube 24 strike the point of the cone 15 and spread throughout the drum, rising along the side of the cone. A dead-air space exists between the cone and the top 12 of the drum, which acts as an insulator, so that heat is not radiated directly from the top of the drum. The products of combustion must fall to the bottom of the drum in order to be drawn off through the chimney or duct 17. The heat is radiated downward, so that the chicks inside the curtain 28 will be thoroughly warmed and the tube 25 will protect the chicks from becoming overheated by too close proximity to the chimney or tube 24.

In the lamp-chamber 6 is the lamp 29 and a supporting device therefor. In the present instance the lamp shown is of a variety which does not require the use of a chimney. The lamp rests upon a board or support 30, having on or integral to its bottom wedges 31. Stops 32 on the upper part of the board 30 hold the lamp in proper place thereon. A stationary stop 33 is provided for a purpose that will be described. Under the board 30 is a frame 34, carrying on its upper side wedges 35, corresponding in position and in inclination with the wedges 31. The frame 34 has a handle 36 extending out through the side of the brooder. The frame 34 is pushed in until it strikes the stop 33. Then

the lamp is placed upon the board 30, and the board is inserted through the door 7, with its wedges upon the wedges of the frame 34. In this position the front end 37 of the board 30 rests against some stationary abutment, such as the side of the brooder. If now the handle 36 is pulled out to the position shown in Fig. 2, the wedges are shifted, the frame 30 moves parallel to the frame 34, and the lamp 29 is raised vertically, so that its cone or chimney 38 fits in the perforation 10 or in the bottom of the chimney-tube 24. In this position the lamp-burner is above the intake of the duct 27. Means for producing the vertical lifting of the lamp is a feature of this invention.

In order to separate the drum 11 from its standard, consisting of the tubes 24 and 25, there is fastened to the bottom 14 of the drum 11 a plate 39, having upon it the hooks 40, and the top casting 18, hereinbefore described, has the plate 41, having the lugs or projections 42 adapted to fit into the hooks 40. The lugs and hooks fasten together in the manner of a bayonet-catch. The drum therefore may be released from its standard by turning it slightly, so that the hooks 40 disengage from the lugs 42, whereupon the drum may be lifted away, and the perforation into the drum is then adapted to permit the insertion of a brush or other cleaning device in order to remove accumulated dirt, soot, &c., from the drum.

The form of brooder shown in Figs. 5 and 6 has a removable roof 1, sides 2 2, a removable floor 4, forming the bottom of the brooder-chamber 5, and a space 6 underneath the floor 4, in which the lamp is supported. The floor 4 rests upon cleats 4^a, fastened to the inner faces of the sides 2. A cleat 4^b may be fastened on the front edge of the floor 4. From the floor 4 depend supporting-arms 43, carrying wedges 44 and bottom pieces 45. A lamp-board 46 carries the lamp 29 and a stop 47 for pushing the lamp into place. The lamp-board 46 carries wedges 48, that are adapted to strike and slide upon the bottom pieces 45. A stop 49 stops the lamp under the perforation 50 under the floor 4 and under the central perforation 10 of the heater. When the lamp is placed upon the board 46 and the board is inserted in place through the door 7, its extremity runs up on the wedges 44, while the wedges 48 are sliding on the front edge of the bottom pieces 45. The lamp is thus lifted vertically into place, so that its burner-cone 38 is opposite the perforation 10, forming the bottom of the inner tube 24.

60 The heater has an inner tube 24, an outer tube 25, a bottom plate 21, having concentric circular ribs 22 and 23, and a concentric rib 50 outside the rib 22. From the bottom plate 21 depend two tubes 51, which extend

into ducts 52, communicating with openings 65 53 through the side walls 2. By these ducts fresh air from the outside is drawn into the space between the inner tube 24 and the outer tube 25 and is discharged through the openings 26, as before. The upper plate 41 70 of the heater provided with the bayonet-catch devices, as heretofore, has also a groove 54, corresponding to the rib 50 in the lower plate, and the last-mentioned groove and rib serve to support a tube 55, of wire-netting 75 which keeps the chicks away from the tube 25, although permitting free movement of air about the heater. Upon the heater is the drum 56, having the flat bottom 57, the cylindrical edge 58, and the inverted-cone 80 top 59, that is supported around its apex by projections 60, extending through the opening in the bottom of the drum from the plate 71, corresponding to the part 18, heretofore described. This drum has no upper flat top 85 12, as in the device heretofore described.

A chimney 17 leads the products of combustion out from the interior of the drum and is set upon the cast-tube 61, fastened to the top 59 of the drum, and extends down inside the drum to near the bottom thereof. From the middle of the cone 59 rises the standard 62 for adjustably supporting the curtain 28. In this embodiment of this invention the standard 62 is screw-threaded, 95 and a nut 63 runs upon the thread of the standard and supports a plate 64, of any suitable material, to the edge of which the curtain 28 is fastened.

As the chicks increase in size the plate 64 100 may be raised, so as to give the chicks more head-room inside the curtain 28. When adjusting the plate 64 up or down, the chimney 17 is temporarily removed.

The brooder of Figs. 5 and 6 is shown without any bottom and is placed directly upon the ground or floor. Air is led into the compartment 6 underneath the floor 4 through openings 65 in the walls 2, and said openings are covered by half-tubes 66, each of which 110 distributes the air in different directions and prevents a direct draft toward the lamp.

The air in the upper compartment 5 is led out through openings 67 in the walls 2 and near the roof by a duct formed by placing a board 68 across one or more of the corners of the chamber 5, so that the openings 67 open into a compartment thus formed behind said board 68. A cap or cover 69 closes the top of said compartment, and openings 70 near 120 the floor 4 lead into said compartment through said board 68.

What I claim is—

1. In a brooder having a perforation through a side wall thereof, and a brooder-chamber, a floor forming the bottom of the brooder-chamber, a lamp supported beneath said floor, a heater in the brooder-chamber comprising a

tubular standard for discharging heated products upward and having a separate air-passage therethrough, a duct connected with said air-passage and extending to a point 5 below the lamp-burner, and a second duct connecting the first-mentioned duct with the perforation through a side wall of the brooder.

2. In a brooder having a perforation through a side wall thereof, and a brooder-chamber, a 10 floor forming the bottom of the brooder-chamber, a lamp supported beneath the floor, a heater in the brooder-chamber comprising a standard consisting of an inner tube adapted to carry heated products upward, a tube 15 outside of said inner tube perforated at its top, and a duct connected with the space between said tubes and extending to a point below the lamp-burner.

3. In a brooder having a perforation through 20 a side wall thereof, and a brooder-chamber, a floor forming the bottom of the brooder-chamber, a lamp supported beneath said floor, a heater in the brooder-chamber comprising a tubular standard for discharging heated products upward and having a separate air-passage 25 therethrough, a duct connected with said air-passage and extending to a point below the lamp-burner, and a second duct connecting the first-mentioned duct with the 30 perforation through a side wall of the brooder.

4. In a brooder having a perforation through a side wall thereof, and a brooder-chamber, a 35 floor forming the bottom of the brooder-chamber, a lamp supported beneath the floor, a heater in the brooder-chamber comprising a standard consisting of an inner tube adapted to carry heated products upward, a tube 40 outside of said inner tube perforated at its top, a duct connected with the space between said tubes and extending to a point 45 below the lamp-burner, and a second duct connecting the first-mentioned duct with the perforation through a side wall of the brooder.

5. In a brooder having a brooder-chamber, 45 a flooring forming the bottom of the brooder-chamber, a heater in the brooder-chamber having a lamp-orifice, a lamp-chamber below said flooring, and means in said lamp-chamber for lifting the lamp vertically to said lamp-50 orifice.

6. In a brooder having a brooder-chamber, a flooring forming the bottom of the brooder-chamber, a heater in the brooder-chamber having a lamp-orifice, a lamp-chamber below 55 said flooring, a support for said lamp in said lamp-chamber, and means for moving said support vertically to insert said lamp into the lamp-orifice.

7. In a brooder-heater, a drum, a tubular 60 standard for said drum for conducting products of combustion thereinto, and releasable locking means between the drum and standard.

8. In a brooder-heater, a drum, a tubular

standard therefor having means of conducting products of combustion into the drum, and releasable connecting means at the bottom of the drum for locking the drum and the standard together.

9. In a brooder-heater, a drum, a tubular 70 standard for said drum for conducting products of combustion thereinto, and a bayonet-catch lock between the standard and the drum.

10. In a brooder-heater, a drum having a 75 perforation in its bottom, a plate fitting said perforation having one member of a bayonet-catch thereon, a standard for said drum for conducting products of combustion thereinto, and a casting on said standard having 80 the other member of said bayonet-catch thereon.

11. In a brooder-heater, a drum having a 85 perforation through its bottom and an inverted hollow cone having its apex pointing downward and set over said perforation, supports between the bottom and apex of said drum, and a standard for said drum having means of conducting products of combustion 90 into said perforation.

12. In a brooder-heater, a drum having a 95 perforation through its bottom and an inverted hollow cone having its apex pointing downward and set over said perforation, a standard for said drum having means of conducting products of combustion into said perforation, and a releasable connection between the standard and the drum.

13. In a brooder-heater, a drum having a 100 perforation through its bottom and an inverted hollow cone having its apex pointing downward and oversaid perforation, a standard for said drum having passage for conducting products of combustion into said 105 perforation, and a bayonet-catch connection between the standard and the drum.

14. A brooder-heater having a standard 110 consisting of an inner and an outer tube and end castings having corresponding ribs or projections for fitting the respective ends of said tubes, the outer tube having an air-inlet at the bottom, and an air-outlet at the top.

15. A brooder-heater having a standard 115 consisting of an inner and an outer tube and end castings having corresponding ribs or projections for fitting the respective ends of said tubes, the outer tube having an air-inlet at the bottom and an air-outlet at the top, a drum having a central perforation, a plate fitting said perforation, and having one member of a releasable connection, the other member of said connection being upon the upper end casting of said standard.

16. A brooder-heater having a standard 120 consisting of an inner tube, an outer tube 125 having perforations near its top and a wire-screen outside of said outer tube, and end castings having sockets for the ends of the

inner, outer and wire tubes, the bottom casting being perforated to admit air between the inner and outer tubes.

17. In a brooder, a brooder-chamber, a heater therein, a screw-threaded support extending upward from said heater, a nut upon said screw-threaded support, a plate sup-

ported by said nut, and a curtain hung from said plate.

GEORGE E. LITTLEFIELD.
